ATTORNEY.

UNITED STATES PATENT OFFICE.

WILLIAM K. AUCHINCLOSS, OF NEW YORK, N. Y., ASSIGNOR TO AMERICAN CAR AND FOUNDRY COMPANY, OF NEW YORK, N. Y., A CORPORATION OF NEW JERSEY.

TANK-ANCHOR FOR TANK-CARS.

1,336,410.

Specification of Letters Patent.

Patented Apr. 13, 1920.

Application filed May 5, 1919. Serial No. 294,657.

To all whom it may concern:

Be it known that I, WILLIAM K. AUCHINCLOSS, residing at 569 West End avenue, New York, N. Y., and being a citizen of the

5 United States, have invented certain new and useful Improvements in Tank-Anchors for Tank-Cars, of which the following is a full, clear, and exact description, such as will enable others skilled in the art to which 10 it appertains to make and to use the same, reference being had to the accompanying drawings, which illustrate the preferred form of the invention, though it is to be understood that the invention is not limited to 15 the exact details of construction shown and described, as it is obvious that various modifications thereof within the scope of the claims will occur to persons skilled in the art.

20 In said drawings:

Figure 1 is a transverse sectional view taken through a fragment of the bottom sheet of the tank of a tank car and transversely through the center sills, showing in 25 end elevation the anchoring means forming the subject matter of this application;

Fig. 2 is a fragmentary side elevational view showing at the upper part in section a fragment of the bottom sheet of a tank, 30 and at the bottom of the view a fragment of the upper portion of the center sill with the anchoring means shown in elevation and partly broken away for purposes of illustration.

35 The object of the invention is to secure in a tank car a low center of gravity, to provide tank anchoring means permanently secured, respectively, to the tank and to the center sill, which anchoring means are so 40 disposed with relation to each other that the assembly of the parts is conveniently arranged so as to permit driving machine driven rivets to secure the anchor to the sills or underframe member of the car with which 45 the anchor is connected, and to the tank.

Referring to the parts, 3—3 indicate the center sills of an ordinary tank car underframe, which sills are ordinarily spaced a 50 convenient distance apart and in the present instance are connected by means of a transversely disposed top sill cover plate 4, which cover plate is preferably of a single sheet extending throughout the entire length of the anchor and is secured to the top flanges 55 of the sills by rivets 5, which rivets may

be machine driven before the tank is placed in position, due to the space surrounding the rivets, which will permit application of the rivet heading means commonly used. The cover plate 4 or equivalent transversely 60 extending member connecting the sills has angular extensions 6—6 which, as will be noted, are beyond the top flanges 7 of the center sills and are spaced some distance therefrom.

65 The flanges 6 are perforated to receive the connecting rivets hereinafter referred to.

Secured to the bottom sheet 8 of the tank is a pair of tank anchoring members which are adapted to secure the tanks to the under-frame and these members consist each of a sheet of metal 9 which is formed at its middle portion 10 of a channel shape, as best shown in Fig. 1, and terminates in flanges 11 and 12, which flanges are angularly disposed 75 with relation to each other, the flanges 11 comprising an upwardly curved portion which extends from the middle channel portion. This upwardly curved portion is of a curvature corresponding to the contour of 80 the bottom sheet 8 of the tank to which it is permanently secured by means of the machine driven rivets 13, and it is to be noted that the rivets 13 should be driven by machinery because they are subjected to great 85 stresses in buffing and pulling, which stresses would, under service conditions, tend to rupture an imperfect connection of the flanges 11 with the bottom sheet of the tank.

An added advantage in a machine driven 90 rivet at this point is that such rivets can be driven with sufficient force to obviate the necessity for calking, something which is quite important in tanks of railway tank cars adapted to carry gasoline and other 95 hydrocarbon fluids.

Intermediate the channel portion 10 of the anchor and the downwardly and outwardly extending flanges thereof, is a shouldered portion 14, which shoulder is of importance 100 in that it provides a seat for the anchor when the parts are in assembled relation.

In practice, the parts are assembled as follows: first, the cover plate 4, or equivalent member, is connected by machine driven rivets to the top flanges 7 of the center sills, with the flanges 6 depending downwardly and outwardly as shown, the anchor members 9 are secured to the bottom sheet 8 of the tank by machine driven rivets, as indi- 110

cated, after which the parts are assembled by lowering the tank to its position upon the underframe, whereupon the shoulders 14 will rest upon the cover plate 4, in convenient proximity to the outer edges of the sill flanges 7 with the extensions 12 lapping and parallel with the flanges 6 of the cover plate, after which the rivets 15 may be driven by suitable rivet driving machine, and it is to be noted that while the space between the top cover plate 4 and the bottom of the tank is only about $1\frac{1}{2}$ in. in an 8000-gallon tank, all of the rivets, due to the disposition of the flanges indicated, may be driven by machinery and when it is desired to remove the tank from the underframe, as for purposes of repair, the rivets 15 may be cut without destruction of any part, except the rivets themselves, the tank removed, repaired and re-placed as before noted.

What I claim is:

1. In an anchor for the tank of a railway tank-car, spaced center sills having upper flanges, a cover-plate connected with said flanges and having lateral extensions projecting outwardly and downwardly therefrom, a tank and anchoring means therefor secured to the tank and lapping said cover plate extensions.
2. In an anchor for the tank of a railway tank-car, spaced center sills having upper flanges, a cover-plate connected with said flanges and having lateral extensions projecting outwardly and downwardly therefrom, and anchoring means for a tank lapping the said outward and downward extensions, riveted thereto and also extending upwardly and outwardly to fit the shell of a tank.
3. In an anchor for the tank of a railway tank-car, spaced center sills having upper flanges, a member spanning said sills and

having extensions projecting below the top plane of said sills, a tank and anchoring means for the tank secured thereto and lapping said extensions.

4. In an anchor for the tank of a railway tank-car, spaced center sills, a transversely extending member connecting said sills and having angular extensions projecting therefrom, and anchoring means for a tank lapping the said extensions, riveted thereto and also extending upwardly and outwardly to fit the shell of the tank.

5. As an article of manufacture, a tank anchor adapted to secure the tanks of railway cars to car underframes and consisting of a sheet of metal formed with a relatively U-shaped middle portion and terminating in flanges angularly disposed with relation to each other, one of said flanges extending upwardly and outwardly and one of said flanges extending outwardly from said middle portion and thence downwardly and both flanges being perforated.

6. As an article of manufacture, a tank anchor adapted to secure the tanks of railway tank cars to a car underframe member and consisting of a shouldered middle portion adapted to rest upon such underframe member and terminating in flanges angularly disposed with relation to each other, one of said flanges being adapted to form a seat for the tank and one of said flanges being adapted to extend below said shouldered portion for connection with said member.

In witness whereof I have hereunto set my hand in the presence of two witnesses.

WILLIAM K. AUCHINCLOSS.
